Fig-4

Fig-5

Figure 1 is a right side elevational view of a powered riding lawn mower embodying my new design;

Figure 2 is a left side elevational view thereof;

Figure 3 is a plan view of the design of Figures 1 and 2;

Figure 4 is a front elevational view of the design of Figures 1-3, inclusive; and

Figure 5 is a rear elevational view of the lawn mower.

I claim:

The ornamental design for a powered riding lawn mower, substantially as shown.
